UNITED STATES PATENT OFFICE.

IRVIN L. BOLINGER, OF CHICAGO, ILLINOIS; MRS. RUTH K. PAGE SOLE HEIR OF SAID BOLINGER, DECEASED.

CATTLE-GUARD.

1,156,856.

Specification of Letters Patent.

Patented Oct. 12, 1915.

Application filed December 2, 1912. Serial No. 734,463.

To all whom it may concern:

Be it known that I, IRVIN L. BOLINGER, a citizen of the United States, and a resident of Chicago, in the county of Cook and State of Illinois, have invented a certain new and useful Improvement in Cattle-Guards, of which the following is a specification.

This invention relates to cattle guards and relates particularly to cattle guards made 10 from sheet metal provided with teeth struck or stamped up from said metal.

The object of the invention is to provide a cattle guard of this type which shall be simple in construction, strong and durable, and which shall be relatively cheap in construction.

To this end, a cattle guard of my invention comprises the various features and details of construction hereinafter described 20 and claimed.

Figure 1 is a top plan view of a cattle guard of my invention shown as applied in use. Fig. 2 is a side view thereof. Figs. 3 and 4 are enlarged fragmentary sectional views taken substantially on the lines 3—3 and 4—4, respectively, of Fig. 2, illustrating the manner of securing the plates on which the teeth are formed to the intermediate cross supports therefor; and Fig. 5 is a 25 fragmentary perspective view, on an enlarged scale, of one of the plates on which the teeth are formed.

Referring now to the drawings, A designates the rails of a railroad track and A' the ties on which said rails are supported.

As shown in Fig. 1 of the drawings, in which I have shown my improved cattle guard as applied in use, said guard comprises a plurality of sections, the finished 40 guard preferably consisting of four sections comprising guard sections on both the inner and outer sides of each rail, and the width of said guard sections being equal to half the distance between the rails, so that said guard 45 sections will entirely fill the space between the rails. Each guard section consists of a plurality of separate bars or plates 1 of suitable sheet metal, preferably sheet steel, the ends of which are rigidly secured to trans- 50 verse members 2, which are designed to rest upon the track ties, and which are preferably formed by means of suitable sheet metal plates or bars bent lengthwise, to form webs 3 and 4, the ends of the tooth bars 1 overlapping the webs 4 and being secured there-

to in any suitable manner, as by rivets, and the webs 3 being disposed in substantially vertical positions and extending approximately at right angles to the webs 4. Said webs 4 afford convenient surfaces to which 60 to attach the ends of the tooth bars 1, while the webs 3 render said cross members very stiff and strong, so that they will easily sustain the weight of an animal or other weight to which they will be subjected in use. 65

The teeth 5 are struck or stamped up from the tooth plates 1 in such manner as to leave continuous webs 6 at each side of said tooth bars which are turned down substantially at right angles to the planes of said tooth bars to form depending marginal ribs or flanges 6 at the edges of said tooth bars. While in Fig. 1 of the drawings, only two 70 of said plates 1 at each side of the guard are shown as toothed, as constructed, all of said plates will be toothed. Said ribs or flanges 75 will greatly reinforce and strengthen said tooth plates considered separately, and collectively will impart such strength to the guard sections that they will easily sustain 80 the weights to which they will be subjected in use.

While my invention contemplates the use of teeth 5 of any desired form and arrangement, I prefer the form and arrangement 85 shown, in which said teeth are triangular in form and are arranged in staggered relation at opposite sides or edges of the tooth bars 1 substantially in the planes of the depending marginal ribs or flanges 6. 90

Between their ends, the tooth bars 1 are braced and strengthened by suitable transverse supports consisting, as shown, of angle bars 7 to which the marginal ribs or flanges 6 on the tooth bars 1 are rigidly connected, and which may be conveniently formed by plates or bars of sheet steel bent into proper form. In the preferable construction shown, the tooth bars 1 are connected to said angle bar supports 7 in the 100 following manner:—Formed transversely in said angular supports at proper intervals to receive the marginal ribs or flanges 6, are slots 8, said slots being of such depth that the lower edges of said ribs or flanges will 105 bear upon the bottoms of said slots, as shown in Fig. 3 of the drawings. After said marginal ribs or flanges 7 have been inserted into the slots 8, they are swaged laterally, 110 preferably inwardly, as shown at 9, whereby

they will be interlocked with the angular supports 7 at the inner edges of said slots. Said transverse supports 7 will operate both to brace the tooth bars laterally and to connect or tie said tooth bars together to form a unitary structure with said transverse supports in such manner that a load imposed on one part thereof will be distributed and sustained by adjacent members. So strong is my improved guard, in fact, that I have been able to dispense with the use of extra length ties as a foundation for said guards and to use ties of standard length, letting the extreme edges of the outside 15 guard sections overhang, without danger of breaking or bending under any usual loads which they sustain in use.

I claim:

1. A cattle-guard comprising a plurality 20 of spaced tooth bars provided with marginal flanges, the teeth on said bars being formed from the portions of said bars between the flanges and comprising spaced series of teeth arranged substantially in the planes 25 of said marginal flanges thereon, substantially as described.

2. A cattle-guard comprising transverse end frame members, and a plurality of spaced tooth bars secured to said end frame members, the lateral edges of said tooth bars being bent to form marginal flanges, and the teeth on said bars being formed from the portions of said bars between the flanges and comprising spaced series of teeth arranged 35 substantially in the planes of said marginal flanges thereon, substantially as described.

3. A cattle-guard comprising transverse end frame members, a plurality of spaced tooth bars secured to said end frame members, the lateral edges of said tooth bars being bent to form marginal flanges, and the teeth on said bars being formed from the portions of said bars between the flanges thereon, a transverse support or supports in-

termEDIATE said end frame members provided with slots which receive the marginal flanges on said tooth bars, and means for connecting said tooth bars and intermediate transverse supports, substantially as described.

4. A cattle-guard comprising transverse end frame members, a plurality of spaced tooth bars secured to said end frame members, the lateral edges of said tooth bars being bent to form marginal flanges thereon, and a transverse angle bar or bars intermediate the end frame members, said angle bar or bars being provided with slots which receive the marginal flanges on said tooth bars and the portions of said marginal flanges which engage said slots being swaged laterally to interlock said ribs or flanges with the sides of said slots, substantially as described.

5. A cattle-guard comprising end frame 65 members, a plurality of spaced tooth bars secured to said end frame members, the lateral edges of said tooth bars being bent to form marginal flanges and the teeth on said bars being formed from the portions of said 70 bars between the flanges thereon and being arranged substantially in the planes of said marginal flanges, and a transverse support or supports intermediate said end frame members provided with slots which receive 75 the marginal flanges on said tooth bars, and means for connecting said tooth bars and intermediate transverse supports, substantially as described.

In testimony, that I claim the foregoing 80 as my invention, I affix my signature in presence of two subscribing witnesses this 14th day of November, A. D., 1912.

IRVIN L. BOLINGER.
